US00D578147S

(12) **United States Design Patent**
Fukano et al.

(10) **Patent No.:** US D578,147 S
(45) **Date of Patent:** ** Oct. 7, 2008

(54) **ELECTRIC ACTUATOR**

(75) Inventors: **Yoshihiro Fukano**, Tsukubamirai (JP);
Ryuichi Masui, Tsukubamirai (JP);
Masaru Saitoh, Tsukubamirai (JP);
Hidemi Yamamoto, Tsukubamirai (JP);
Hirofumi Watanabe, Tsukubamirai (JP)

(73) Assignee: **SMC Corporation**, Chiyoda-ku, Tokyo (JP)

(**) Term: **14 Years**

(21) Appl. No.: **29/301,641**

(22) Filed: **Mar. 11, 2008**

(30) **Foreign Application Priority Data**

Sep. 11, 2007 (JP) 2007-024748

(51) **LOC (8) Cl.** **15-09**

(52) **U.S. Cl.** **D15/143**

(58) **Field of Classification Search** D13/158, D13/162, 184; D15/5, 7, 9, 143, 148, 149; 74/89.15, 490.09; 310/10, 12, 15, 20, 80, 310/300

See application file for complete search history.

(57) **CLAIM**

The ornamental design for an electric actuator, as shown and described.

DESCRIPTION

FIG. 1 shows a front view of an electric actuator showing my new design;

FIG. 2 shows a rear view thereof;

FIG. 3 shows a top view thereof;

FIG. 4 shows a bottom view thereof;

FIG. 5 shows a left side view thereof;

FIG. 6 shows a right side view thereof;

FIG. 7 shows a top, front and left side perspective view thereof; and,

FIG. 8 shows a top, rear and right side perspective view thereof.
